UNITED STATES PATENT OFFICE

2,292,819

BAFFLE RING FOR POT TYPE BURNERS

James L. Breese, Santa Fe, N. Mex., assignor to
 Oil Devices, Santa Fe, N. Mex., a limited partnership of Illinois

Application January 9, 1939, Serial No. 249,993

1 Claim. (Cl. 220—40)

My invention relates to an improvement in pot type liquid hydrocarbon burners and has for one purpose the provision of an improved connecting means between the pot of such a burner and the baffle thereof.

Another purpose is the provision of means for holding the top baffle of such a pot firmly in position normally, while permitting its ready removal.

Another purpose is the provision of improved means for assembling a pot and the baffle of a pot type burner.

Other purposes will appear from time to time in the course of the specification and claim.

I illustrate my invention more or less diagrammatically in the accompanying drawings wherein:

Fig. 1 is a vertical axial section through the pot;

Fig. 2 is a similar section through the baffle ring on an enlarged scale;

Fig. 3 is a plan view on an enlarged scale of the baffle ring shown in Fig. 2;

Fig. 4 is a plan view of the structure of Fig. 1; and

Fig. 5 is a section on the line 5—5 of Fig. 4.

Like parts are indicated by like characters throughout the specification and drawings.

Referring to the drawings, I generally indicate a cylindrical or slightly conic pot wall having a bottom 2, herein shown as integral, and a plurality of primary air inlet apertures 3. 4 indicates a top row of secondary air apertures more closely spaced than the primary air apertures 3. 5 indicates any suitable connection for a liquid fuel inlet.

The upper edge of the pot is outwardly flanged as at 6 with a downwardly extending circumferential lip or flange 7. 8 generally indicates an upwardly and inwardly extending conic baffle body having an outer flange 9 and a connecting offset portion 10. As will be clear from Fig. 2, there are two flanges 9, each such flange having an upwardly extending end boss 11 at one end thereof. As the flange extends about the periphery of the ring from said boss it decreases successively in width until it terminates at a point 12 which is of minimum width. 13 indicates a recess between each reduced end 12 of one of said flanges and the enlarged end and boss 11 of the opposite flange.

Spot-welded or otherwise secured to the flange 6 of the burner or pot I illustrate a pair of oppositely spaced clips 20, each such clip having a portion 21 engaging and secured to the member 6, an upstanding portion 22, and a clip portion 23 with a downward offset or bend 24 intermediate its ends.

The ring 8 may be laid on the top of the pot with the lower face of the portion 9 engaging the upper face of the lip or flange 6 of the pot. The ring may then be rotated about its axis, and such rotation may be employed to cause small vertical lugs or bosses 11 to snap into the clip and seat in the space between the downward offset 24 and the upstanding portion 22. The result is a locking action sufficiently firm to hold the ring in place while permitting its easy removal, simply by twisting in the reverse direction, in the event that removal is necessary.

My invention may be applied to the initial assembly of the parts, in shipment or at the point of use, and permits ready removal of the ring for replacement, cleaning or the like.

It will be realized that whereas I have described and illustrated a practical and operative device, nevertheless many changes may be made in the size, shape, number and disposition of parts without departing from the spirit of my invention. I therefore wish my description and my drawings to be taken as in a broad sense illustrative or diagrammatic, rather than as limiting me to my precise showing.

I claim:

In combination, a pot shaped receptacle having an integral upper, outwardly extending annular flange, an annular cover ring having a central aperture and including a flange portion opposed to and conforming to the top of said annular flange, and an adjacent portion penetrating and conforming generally to an upper part of the interior of the receptacle in a snug fit, spring latches secured on the receptacle flange, and upwardly extending lugs on the flange of the ring adapted, on rotation of the ring, to be brought into engagement with the spring latches, said latches including downwardly turned portions adapted to snap over said lugs, the width of the ring flange varying from a maximum at each said lug to a minimum adjacent the next lug.

JAMES L. BREESE.
